UNITED STATES PATENT OFFICE.

CARL F. GERLINGER, OF DALLAS, AND HEINRICH HARTWIG, OF SALEM, OREGON.

RAILWAY-SWITCH.

1,151,941.

Specification of Letters Patent. Patented Aug. 31, 1915.

Application filed May 3, 1915. Serial No. 25,488.

To all whom it may concern:

Be it known that we, CARL F. GERLINGER, a citizen of the United States, residing in Dallas, in the county of Polk and State of Oregon, and HEINRICH HARTWIG, a citizen of the United States, residing in Salem, in the county of Marion and State of Oregon, have jointly invented certain new and useful Improvements in Railway-Switches, of which the following is a specification.

This invention relates to railway switches of the class which are provided with mechanism whereby the switch may be operated either by hand or automatically and our invention relates particularly to switches of this kind in which two switch points or rails are connected together for simultaneous adjustment to enable a train moving in one direction to continue on the main line, or a train moving in the same direction to pass from a siding to the main line, in either case automatically and properly setting and locking the switch points, such mechanism being also so constructed that a train moving in the opposite direction on the main line will continue on the main line unless the switch has been set and locked for the siding. The mechanism which we employ is so constructed and organized that the switch points are positively moved toward and from the rails and when the switch points are in intermediate position, *i. e.*, are neither set for the main line nor for the siding, the switch-operating mechanism is in such position that a train moving in either direction from either the main line or the siding will automatically move the switch points in the proper direction to cause the train either to continue on the main track or to pass to the siding according to the particular existing conditions.

The mechanism which is directly operated by the wheels of the train comprises levers and rock shafts which are connected with novel mechanism in a switch stand, such mechanism comprising a lever which is pivoted within the casing of the switch-stand and is jointed to an arm projecting from a hollow rock shaft or sleeve within which is a shaft fast with a disk carrying a pin engaging a recess in the end of the lever. Said disk is connected by a horizontally arranged rod with the switch points and as the disk is turned the switch points are shifted. The disk is also provided with two pins, one on each side of the pin first mentioned, and

these pins are so arranged that they co-operate with the lever in turning the disk back to the position from which it was moved. The first mentioned pin which engages the recess in the lever also co-operates with the lever to lock the latter and in turn lock the switch points when said lever and disk have been moved to the full extent in either direction. The rod to which the disk is attached carries a visible signal of ordinary construction which indicates visibly the position of the switch mechanism, and the sleeve which surrounds said rod is connected with an operating hand-lever by moving which the switch mechanism may be so operated as to place the switch points in any desired position. Said lever is so mounted that when in its midway position it cannot be depressed or locked but it is free to move and thus permits the sleeve to be moved without obstruction, but when the lever is moved to its full extent in either direction it may be lowered and locked in such manner as to prevent an unauthorized person from raising it to operative position.

Our invention will be hereinafter more fully explained and the details of construction will be more particularly described.

In the accompanying drawings, Figure 1 is a plan view of a main line and siding with our improved switch mechanism applied, the switch-stand being shown in horizontal section. Fig. 2 is a detail view in perspective showing particularly the switch-stand and some of the mechanism connecting the switch-stand mechanism with the switch-operating levers of the tracks. Fig. 3 is a detail view partly in side elevation and partly in section showing our safety device which is so constructed that should the switch points be improperly set for either the main line or the siding, that is, should they be in an intermediate position as shown in Fig. 1, the switch-operating mechanism will be automatically operated to properly set the points. Fig. 4 is a view similar to Fig. 1 showing the mechanism shifted to connect the main line with the siding. Fig. 5 is a detail view mainly in vertical section of the switch box and its mechanism. Fig. 6 shows a section on the line 6—6 of Fig. 7. Fig. 7 is a view partly in side elevation and partly in section of the switch-stand and some of the mechanism connected therewith. Fig. 7^a is a detail view showing the operating lever in locked position. Fig. 7^b is a de-

tail view in perspective of parts of the switch stand. Fig. 8 is a detail view in perspective of the outside rail of the siding showing the horizontally arranged lever associated therewith and which is connected with the switch-operating mechanism. Fig. 9 is a view similar to Fig. 8 showing the connections between the lever of the main track and the switch-operating mechanism. Fig. 10 shows a transverse section on the line 10—10 of Fig. 8. Fig. 11 shows a transverse section on the line 11—11 of Fig. 9.

The rails of the main track are indicated at A, A', and the rails of the side track or siding are indicated at B, B'.

C indicates a rock shaft below the rails and provided with arms D, D' projecting in the opposite directions as most clearly shown in Figs. 8 and 9. Said rock shaft is mounted to turn in suitable supports or brackets b clamped to the rails A', B' as best shown in Figs. 10 and 11. The arm D extends forwardly from the rock shaft and is pivotally connected with an arm a' projecting downwardly from a lever E pivoted at e to the outer side of the rail A' of the main line, while the arm D' projects rearwardly or to the right and is pivotally connected with an arm b' projecting downwardly from a lever F pivoted at f to the track rail B' of the siding. It will be observed that the levers E and F have portions which are adapted to stand above the rails A', B' and they are also adapted to receive the tread of the wheels of an engine, car or train traversing the track. Both the levers E and F are shown slightly elevated above the rails and when in this position the arms a' and b' of the rock shaft will occupy the positions shown. At this time also the switch rails X, X' are in the position shown in Fig. 1. Said switch rails, it will be observed, are connected with each other by cross pieces x so that they will move simultaneously and coincidentally, being preferably pivoted at y, as indicated in Fig. 1.

The rock shaft C carries at one end an upwardly projecting arm H which is jointed to a horizontally arranged rod I extending to an arm J projecting upwardly from a horizontally arranged rock shaft K arranged at right angles to the rod I. Said rock shaft is mounted in bearings in suitable supports k, the details of which are unimportant. Said arm J is also connected by a horizontally arranged rod M with a lever N jointed at n to a horizontally arranged lever O pivoted at o to one of the rails A of the main track. Said lever N projects downwardly from the horizontally arranged lever O and carries a roller n' adapted to ride on a cam surface P which has a central raised portion p and on opposite sides of this there are concaved por-

tions p'. When the lever O is raised and lowered a corresponding movement is given to the arm J and consequently to the rock shaft K, and it is also understood that as the levers E and F are raised and lowered the rock shaft K is correspondingly turned. The rock shaft K carries an upwardly projecting arm Q which is connected by a rod q with a horizontally arranged rocking lever R within the switch box S. This lever R is pivoted to a block R' connected with the base of the switch box by screws r which pass through slots r' in the block R', this means of attachment providing for a slight adjustment on the block R' which may be regulated by a set screw r².

T indicates an arm jointed to the lever R at t' secured by a set screw t or in any other suitable way made fast to a vertically arranged sleeve T' which extends upwardly through the hollow column s of the switch-stand, and U indicates a rod extending upwardly through the sleeve T' and also downwardly through the sleeve into a socket in the base of the casing and it is made fast, as indicated at v, to a horizontally arranged disk V which carries on its upper side three pins, 1, 2, and 3. This disk is connected by means of a horizontally arranged rod W to the switch points. The middle pin 2 of the disk is adapted to engage a recess w in the end of the horizontally arranged lever R and it normally so engages said recess, while the pins 1 and 3 are normally out of engagement with the lever.

Assuming that the mechanism is in the condition shown in Fig. 1, if the rock shaft C is operated to actuate through the mechanism before described the lever R and to turn it in either direction, it is obvious that the disk V will be turned. If, for instance, the lever R is turned to the right the parts will be made to assume the position shown in Fig. 4, the disk having been moved to this position by the lever R, but it will be observed that the pin 2 has left the recess w and now engages the end of the lever on the left hand side of said recess. When the parts are in this position the disk is locked in such manner that the switch points cannot be accidentally moved by a force exerted on the switch points or rod W. If now the lever R be moved to the left from the position shown in Fig. 4, it will strike the pin 1 and move the disk in the opposite direction and until the pin 2 comes into the recess w. The mechanism operates in the same way when the lever R is turned in the opposite direction to that shown in Fig. 4, the pin 3 being then employed to reset the disk. The device shown at w' is merely to indicate how the rod W may be attached to the opposite side of the disk 130

when the switch box is set on the opposite side of the track.

The sleeve T' before referred to carries at its upper end a horizontally projecting arm Z which is clamped to the sleeve by the devices shown and this arm carries an operating lever Z' pivotally connected to the arm at z . This lever, when in an intermediate position, is disposed horizontally, as indicated in Figs. 2, 6 and 7, being at that time supported on a flange z' on the upper surface of the head Z^2 of the standard s beneath the arm Z . As shown the head Z^2 is formed with a segmental recess z^4 and with grooves z^2, z^3 extending from the recess z^4 on opposite sides of the flange z' to the periphery of the head. The lever Z' , it will be observed, is formed with a nose or projection q' which is adapted to move radially through the grooves z^2, z^3 and also transversely in the recess z^4 . When the lever Z' is in an intermediate position the nose or projection q' assumes the position shown in Fig. 7 and rests on the flange z' , but when the lever is moved either to the right or to the left to a certain extent the nose q' comes opposite one of the grooves z^2, z^3 and when the lever is in this position it may be depressed in the manner indicated in Fig. 7^a and the nose q' of the lever may then enter one of the grooves and pass into the recess z^4 . When in such position the lever Z' may be lowered and may be secured in any suitable way as by a padlock P^2 applied to a perforation z^5 in the lever. When thus locked the lever cannot be raised to operative position by an unauthorized person. But it will be observed that at all times the mechanism in the switch stand is in such condition that the switch may be automatically shifted whatever be the position of the lever Z' .

The manner in which the mechanism operates under various conditions has heretofore been referred to, and it will be understood that if the mechanism is in the condition shown in Fig. 1 both the main track and the siding are disconnected and there is danger of derailment. If a train approaches on the main track from right to left as viewed in Fig. 1, the lever E will be depressed. This would so turn the rock shaft C as to push the rod I and through the rock shaft K and the rod q will pull the lever R to the left. Through the mechanism before described the rod W will be pulled toward the switch-stand and will thus set the switch rails for the main track. At the same time the rod M will be pushed to the left, as viewed in Fig. 1, and will set the roller n in the concave p' at which time the lever O will be below the level of the rail A and the train will proceed on the main track. In like manner, referring to Fig. 1, if the mechanism is in the position there shown,

and a train approaches on the side track the lever F will be depressed and the lever R in the switch-stand will be moved to the right, in the manner indicated in Fig. 4. This will move the rod W toward the track and cause the switch rails to be shifted, in the manner indicated in Fig. 4, so as to so set the switch that a train can pass from the siding to the main track. When this takes place the rod M is pulled in such manner as to set the roller n' just over the top of the projection p and in the concave p^2 but if after the train has passed the switch rails be then entirely disconnected from the rails of the main track as indicated in Fig. 1, the roller n' will again pass over the projection p to the position shown in dotted lines in Fig. 3, so that when the lever O is next operated it will set the switch for the main track.

It will be observed that when the lever R is shifted, in the manner indicated in Fig. 4, from the position shown in Fig. 1 the disk B is moved by reason of the engagement of the pin 2 in the recess w . As the disk continues to rotate the pin 2 leaves the recess w and engages the outer end of the lever R and locks it so that the switch points cannot be displaced accidentally. When the parts are moved back to their original position the outer end of the lever R strikes against the pin 1 and moves the disk toward its original position and until the pin 2 enters the recess w . The pin 3 on the disk performs a similar function in resetting the disk. It will also be understood that the lever Z' moves correspondingly with the arm T , being connected to move therewith through the sleeve T' , and it will also be understood that the lever Z' may be made to operate the switch mechanism by hand, in substantially the same way that it is operated automatically.

If the lever Z' is left in a horizontal position or is not properly locked it may be displaced in such manner as to cause the switch points to separate from the rails or occupy a position such as shown in Fig. 1. If this were so, and a train were approaching the switch from left to right on the main track, the lever O will prevent accident. Let it be assumed that the last train passing the switch has been on the main track and had set the switch for the main track but that the switch rails had become separated from the rails of the main track as indicated in Fig. 1. The roller n' would then be raised to the position shown in full lines in Fig. 3 at the upper end of the concave p' but not on top of the middle portion p . At this time the lever O would be above the rail and the wheels would depress this lever, causing the roller n' to move farther down in the concave p' . This would so move the switch mechanism in the manner before described as to properly

set the switch rails for the main track. It is therefore obvious that it is impossible for a train to pass the switch in either direction without operating properly the mechanism 5 to close the switch so that there is no danger of derailment, and the mechanism is also such that there is no possibility of injury to the outer ends of the switch rails or points as they are always drawn close up against 10 the rails when a train passes.

We claim as our invention:—

1. A railway switch, comprising a switch-stand, mechanism within the switch-stand and connected with the switch rails for 15 shifting them, a rock shaft associated with the tracks, levers operatively connected with the rock shaft and adapted to be engaged by the wheels of the train, another rock shaft connected with that first mentioned, con- 20 nections between said last mentioned rock shaft and the switch rail operating mechanism in the switch-stand, and means within the switch-stand for locking the rail-shifting mechanism.
2. The combination with a switch-stand, of switch rails, a disk within the switch-stand connected with the switch rails, a lever pivotally mounted within the switch-stand and operatively connected with the 25 disk, a lever associated with the tracks, mechanism connecting this lever with the lever in the switch-stand, and connections between the disk and the lever in the switch-stand for resetting the mechanism therein.
3. The combination with a switch-stand, of a lever pivotally mounted therein, a vertically arranged shaft mounted in the switch-stand, an arm secured thereto and jointed to the lever in the switch-stand, and 30 a disk pivotally mounted within the switch-stand and carrying a pin engaging said lever and carrying also other pins adapted to engage said lever for resetting the mechanism.
4. The combination with a switch-stand, of a lever pivotally mounted therein, a sleeve mounted in the switch-stand, an arm attached thereto and jointed to said lever, a disk pivotally mounted within the switch-stand, switch rails connected with said disk, means for moving the lever in the switch-stand, a pin carried by the disk engaging a 40 recess in said lever and adapted also to engage the end of the lever on opposite sides of 45 said recess to lock the mechanism, and other pins carried by the disk which are engaged by said lever for the purpose of resetting the disk, substantially as described.
5. The combination with the rails, of a

switch-stand, a lever pivotally mounted 60 therein, a rock shaft, connections between said rock shaft and said lever, another rock shaft associated with the track rails, connections between the two rock shafts, a lever associated with the track rails and opera- 65 tively connected with one of said rock shafts, a disk pivotally mounted within the switch-stand and connected with the switch rails, and connections between the disk and the lever in the switch-stand whereby the 70 turning of the lever causes corresponding movement to the disk and shifts the switch rails.

6. The combination of a switch-stand, a lever pivotally mounted therein, a disk pivotally mounted within the switch-stand and adapted to be connected with the switch rails, a sleeve mounted in the switch-stand, an arm carried by the sleeve and connected with the lever in the switch-stand, a hand lever connected with said sleeve, and a support for said hand lever for holding it in horizontal position and which is recessed to allow the lever to turn to a vertical locking position.

7. A railway switch, comprising means for setting it to the main line for a train moving in one direction from either the main line or the siding, a lever on the main line operated by the wheels of the 90 passing train, a roller suspended from said lever, a cam surface engaged by the roller, and a connection between said roller and the switch-operating mechanism for closing the switch should it be accidentally left in neutral position.

8. The combination with switch rails of mechanism for setting them for a train approaching the switch in one direction from either the main line or the siding, a lever 100 operated by a train approaching the switch on the main line in the opposite direction, a link depending from said lever, a roller carried thereby, a cam surface engaged by the roller and which has a central raised portion and concave portions on opposite sides, and a connection between said link-suspended roller and the switch-operating mechanism for positively closing the switch should it have been left in neutral position. 110
